United States Patent Office

Des. 219,524
Patented Dec. 22, 1970

219,524

MODEL RACING CAR

Eric Harrison Broadley, Flackwell, England, assignor to
Lola Cars Limited, Slough, England

Filed Aug. 25, 1969, Ser. No. 18,841

Term of patent 7 years

Int. Cl. D21—02

U.S. Cl. D34—15

FIG. 1

FIG. 2

FIG. 3

FIG. 4

FIG. 1 is a side elevation view of the model racing car,
FIG. 2 is a front elevation view thereof,
FIG. 3 is a top plan view thereof, and
FIG. 4 is a rear elevation view thereof.

The opposite side of FIG. 1 is identical to the side shown.

I claim:

The ornamental design for a model racing car, as shown and described.
